UNITED STATES PATENT OFFICE.

WILLIAM W. DAVIS, OF BALDWIN, MICHIGAN, ASSIGNOR OF ONE-HALF
TO GEORGE F. DUFFING, OF BALDWIN, MICHIGAN.

PROTECTOR-PLATE FOR SHOVELS.

SPECIFICATION forming part of Letters Patent No. 767,739, dated August 16, 1904.

Application filed November 30, 1903. Serial No. 183,219. (No model.)

To all whom it may concern:

Be it known that I, WILLIAM W. DAVIS, a citizen of the United States, residing at Baldwin, in the county of Lake and State of Michigan, have invented a new and useful Protector-Plate for Shovels, of which the following is a specification.

This invention relates to guards for shovels, and particularly to a detachable device which can be easily applied to an ordinary shovel without altering the shovel or requiring the services of a mechanic.

The device is a step-piece or boot-protector which can be easily applied on railroad-shovels, and it is especially advantageous in use when employed in connection with tamping, whereby the foot or foot-covering is efficiently protected from contact with the shovel.

The peculiar novel construction of the device will be specifically set forth in the following description and illustrated in the accompanying drawings, in which—

Figure 1 is a plan view of a shovel, showing my invention applied. Fig. 2 is a sectional view on the line 2 2 of Fig. 1. Fig. 3 is a sectional view on the line 3 3 of Fig. 1, and Fig. 4 is a detail perspective view of one of the guards.

In the preferred form of my invention, as illustrated in the accompanying drawings, 1 designates a curved plate of gradually-increasing width from one end to the other. From opposite edges of the plate 1 are right-angularly-disposed flanges 2 and 3, curved to conform to the curvature of the edges 4 and 5 of the plate. At the widest end of the plate the flanges diverge to provide a flared opening 6 to permit the guard to be guided upon the shovel-blade. The flanges near the opposite

end of the plate assume positions in approximate parallelism to each other, with their free edges slightly inclined toward one another, so that when the plate is guided upon the shovel the flanges will grip the blade and effectually prevent accidental displacement of the guard. 40 If desired, a spur 7 may be cast upon the wide end of the plate 1 to be driven into the handle of the shovel to effectually prevent a longitudinal movement of the guard. This construction will be quite enough to insure the proper 45 attachment of the shovel and guard, although, if desired, a perforated ear 10 may be cast upon the flanges, whereby the guard can be fastened to the shovel.

Of course it is to be understood that the 55 guards are to be made in rights and lefts, so that either or both sides of the top of the shovel may be supplied therewith.

Having thus described the invention, what is claimed is—

A device of the class described comprising a plate which is increased in width at one end and provided with an integral spur at its wide end, integral flanges extending throughout the opposite edges of the plate and converged 65 toward their outer edges, said flanges following the edges of the plate and thereby diverged at the wide end of the plate, one of the flanges having an intermediate perforate ear projected at the outer edge thereof. 70

In testimony that I claim the foregoing as my own I have hereto affixed my signature in the presence of two witnesses.

WILLIAM W. DAVIS.
